E. E. JOHNSON

BRACE

Filed May 8, 1922

Inventor:
Ewald E. Johnson
by Benjamin, Rodhouse & Lundy
Attns.

UNITED STATES PATENT OFFICE.

EWALD E. JOHNSON, OF ST. CHARLES, ILLINOIS.

BRACE.

Application filed May 8, 1922. Serial No. 559,234.

To all whom it may concern:

Be it known that I, EWALD E. JOHNSON, a citizen of the United States, residing at St. Charles, in the county of Kane and State 5 of Illinois, have invented a new and useful Improvement in a Brace, of which the following is a specification.

My invention relates to braces, and more particularly to what is known as a hand 10 brace or drill of the ratchet type.

The principal object of my invention is to provide a convenient tool of this character that is adapted to be manipulated so that boring and drilling in inconvenient or 15 restricted places may be accomplished. A further object is to provide a structure wherein the modified tool may be provided without the necessity of using additional parts or eliminating any of the parts already 20 on the tool. In this connection I have provided a structure that does not alter the normal functioning of the tool and by interchanging and adjusting certain of the elements a convenient form is provided that 25 is materially reduced in length from the ends of the bit jaws to the hand grip. I have designed this tool especially for use in connection with the work of persons in installing telephone and electric wires in a 30 building, where it frequently occurs the operator is required to bore or drill a hole through joists, and in such positions the ordinary brace and bit are not available where the hole it is desired to bore is to be located 35 transversely through one or more joists which usually are arranged or spaced on 14 to 16 inch centers, which would not of course permit of the positioning of the brace in the usual manner, nor allow the operator to 40 exert any considerable pressure upon the handle or grip. I prefer to carry out my invention in substantially the manner hereinafter fully described, and as more particularly pointed out in the claims, reference 45 being now had to the accompanying drawings forming a part hereof, in which

Fig. 1 is a side elevation of my improved brace showing a broken away portion in section.

50 Fig. 2 is a top plan of the brace with the parts interchanged and positioned for convenient operation in a relatively narrow space.

55 Fig. 3 is a longitudinal section on line 3—3, Fig. 1, partly broken away and enlarged.

Fig. 4 is a sectional view taken on line 4—4, Fig. 1 and enlarged.

Fig. 5 is a transverse enlarged section on line 5—5, Fig. 1.

Fig. 6 is a fragmentary view of a portion of a brace showing a modified construction, and

Fig. 7 is a transverse section on line 7—7, Fig. 6.

In the drawings, similar reference characters have been employed to designate the same parts wherever they occur throughout the several views, and by referring first to Fig. 1, it will be seen the brace preferably comprises the usual bit or tool chuck 10 in which the clamping jaws 11 are mounted, and having pawl and ratchet elements 12 connecting the same to a sleeve 13 having a lateral socket 14 to receive the adjacent end 15 of a suitably U-shaped operating crank 16 for rotating the structure. The usual rotatable handle 17 is provided upon the connecting member of the U-shaped crank, and the lateral or outer end of the crank is provided 75 with a head 18 to which the hand grasp is removably attached.

In order to permit the hand grasp to be removably mounted upon head 18, I have counterbored the outer end of the latter to provide therein a recess 20 and a concentric inwardly extending shoulder or flange 21, as seen in detail in Fig. 3. The hand grasp is provided with an embossment 22 extending axially from the same which is provided with a longitudinally or axially disposed recess 23. A pair of oppositely arranged pawls 24 having substantially arrow or hook shaped heads at their outer ends are pivotally mounted upon a transverse pin 25 inserted through embossment 22, and said ratchet pawls are conveniently mounted upon said pivot pin 25 with their headed ends projected beyond the end of embossment 22. A U or V-shaped spring 26 is interposed between the adjacent faces of the pawls and exerts its pressure or power to move the jaws normally away from each other. Headed release studs 27 mounted in alining apertures in embossment 22 have 100 their heads 27^a positioned between the outer faces of the pawls and the inner surfaces of the wall of the embossment so that by pressing the projecting ends of studs 27 inwardly towards each other the operator may 105 compress springs 26 and cause pawls 24 to release their arrow shaped heads from shoul-

der or flange 21 on head 18 of the crank to remove the hand grip from the same.

A similar counterbore 28 is made in the end of the bit stock opposite the chuck jaws 11 and provides an inwardly extending flange or shoulder 29 to receive and be engaged by the heads of pawls 24. This permits hand grip 18 to be released from the head of the crank, and its pawls engaged 10 with counterbore 28, just mentioned, so that the pressure may be exerted directly against tool stock 10, and it will be seen the distance between the work end of the tool and the hand grip has thus been materially reduced, 15 and the operator may, in restricted spaces, engage his hand with the grip to support the tool. The crank may be utilized for the purpose of ratcheting the tool, and in order to do this and give the operator greater lever- 20 age than the length of arm 15, I have adjustably connected said arm with socket 14 in the manner shown in Figs. 4 and 5. This structure consists in forming a plurality of concave notches 30 upon the circumference 25 of arm 15 of the crank, which is within socket 14, and coacting therewith is a retractable plunger pin 31 that is yieldingly and reciprocably mounted in the bore 32 of an enlargement 33 on the socket; said bore 30 having its axis tangent to the bore of the socket and the surface of arm 15. The pin 31 is provided with a head 34 upon its inner end that is kept pressed normally towards a shoulder 35 in bore 32 by means of a small 35 expansion spring 36 interposed between head 34 and a screw plug 37 tapped into the outer end of the bore. The plunger pin 31 is of cylindrical cross-section throughout its length, and intermediate its ends is pro- 40 vided with a concaved recess 38, as seen in Fig. 5. This permits the inner end portion of pin 31 to be normally engaged with one of the concave recesses 30 in the adjacent portion of arm 15 of the brace crank and 45 prevents its accidental removal or rotation in socket 14. By pressing plunger pin 31 inwardly until concave recess 38 is positioned upon the adjacent portion of arm 15 the latter with the crank may be turned, un- 50 til it assumes a position similar to that shown in Fig. 2, or transverse to the axis of the crank. The plunger pin 31 is then 55 released, and the cylindrical inner portion of the pin will again seat in recess 30 at a right angle to the recess previously engaged by the pin. The outer end of the crank may then be used to ratchet the tool, and the operator may exert pressure against hand grip 19 in the usual manner without experienc- 60 ing any difficulty in operating the tool.

In the modification shown in Fig. 6, crank

16 has its arm 15 mounted in a manner similar to that previously described, but said arm is adapted, when plunger pin 38 is pushed inwardly, to be removed from socket 14 instead of moved to the position of Fig. 3. As seen in Figs. 6 and 7, arm 15 is inserted into the inner of two telescoping tubes that are secured to and extend axially from the socket so that when arm 15 is removed the outer tube 39 may be slid longitudinally upon the inner tube 40 until the same assumes the position shown in the dotted lines, whereupon the elongated structure may be operated as a lever to ratchet the tool in the manner of the preferred form. The outer tube carries a pin 41 that operates in a longitudinally elongated slot 42 in the inner tube so that the tubes may not be disassembled.

From the foregoing it will be seen the brace is well adapted for use in restricted spaces, and, when the preferred form is employed, there are no loose parts that may be left lying around and liable to be lost, and I have employed elements in this structure that are interchangeable so that the alternate type of the tool contains all of the parts of the common structure.

What I claim is:

1. A brace comprising a chuck member having a counterbored rear end, a U-shaped crank carried by said chuck and operable therewith and having a counterbored outer end, a removable hand grip having latch dogs pivotally carried thereby and adapted, respectively, to engage said respective counterbores, and means for movably securing said crank to said chuck whereby said crank may be adjusted to a position at right angles to its normal position and thereby provide a lever at substantially a right angle to the axis of the chuck.

2. A brace comprising a chuck member having a counterbored rear end, a U-shaped crank carried by said chuck and operable therewith and having a counterbored outer end, an interchangeable hand-grip having latch dogs normally engaged in the counterbored end of said crank and adapted to be removably mounted on the counterbored rear end of said chuck, and means for movably securing said crank to said chuck whereby the same may be moved to an angle to said chuck to provide an operating lever when said hand grip is transferred to said chuck.

Signed at St. Charles, county of Kane and State of Illinois, this 1st day of May, 1922.

EWALD E. JOHNSON.
